UNITED STATES PATENT OFFICE.

THOMAS WILLIAM HALL, OF LONG BEACH, CALIFORNIA, ASSIGNOR OF ONE-HALF TO
CHARLES KNUTSON, OF LONG BEACH, CALIFORNIA.

SAFETY COLLAPSIBLE COMBINATION STEPLADDER AND STOOL.

Application filed December 11, 1922. Serial No. 696,198.

To all whom it may concern:

Be it known that I, THOMAS WILLIAM HALL, a citizen of the United States, residing at Long Beach, in the county of Los Angeles and State of California, have invented a new and useful Safety Collapsible Combination Stepladder and Stool, of which the following is a specification.

This invention relates to that class of devices in which the top of a step ladder is broad enough to form a seat, and in which the ladder and seat are adapted to be collapsed; and in which the top is intended to be used as a support for the feet of those wishing to reach higher than the steps of the ladder.

An object of the invention is to provide such a device with a broad seat and at the same time make provision for maximum security against tilting or collapsing, and to provide for collapsing the ladder to minimum space both in thickness and in length.

An object of the invention is to so construct the stool that it can be handled with ease and convenience by one hand for collapsing and setting up the ladder and for moving it from place to place in its spread step ladder form.

In this invention the top of the step ladder and stool is formed of a tread and seat piece fixed to the top of the ladder frame and a tread piece hinged at its rear edge to the front edge of the fixed tread piece, and hinged to the rear side of the top of the prop that supports the ladder aslant when the ladder is set up; and a brace pivoted to the ladder near the underside of the fixed top tread and seat piece and pivoted to the prop at such distance from the hinged tread piece, that when the ladder is set up it firmly stands.

Other objects, advantages and features of invention may appear from the accompanying drawing, the subjoined detailed description and the appended claim.

The accompanying drawing illustrates the invention.

Figure 1 is a side view of the appliance constructed in accordance with this inven-

tion; showing it erected for use either as a 50 step ladder or stool.

Fig. 2 is a front view of the appliance.

Fig. 3 is a side view of the appliance in collapsed standing position ready to be transported or stored away; or as it would appear when lifted from the floor.

Fig. 4 is an enlarged fragmental section on line x^4 , Fig. 2.

Fig. 5 is a section on line x^5 , Fig. 1, looking upward at the top of the step ladder 60 stool.

Fig. 6 is an edge elevation of one of the bearing stud bars.

Fig. 7 is an enlarged fragmental view of the hinge for connecting a prop to the stool 65 seat plate.

The appliance comprises a seat piece or top tread 1 that is formed of a fixed or front tread and seat piece 2 and a hinged or back tread piece 3 which is hinged at its rear edge 70 to the front edge of the fixed tread piece by the hinges 4.

A pair of step ladder legs 5 are rigidly secured to piece 2 by the angle plates 6 and screws 7; and these legs are arranged to incline forwardly, outwardly and from under the plate 2 when it is held in a horizontal plane. That is, when the fixed seat piece 2 is held in a horizontal plane the step ladder legs incline forwardly from the top down 80 at about an angle of twenty-two degrees, and sidewise about nine degrees.

A pair of rear legs 8 are pivotally connected to the underside of the hinged tread piece 3 by means of the bars 9 secured by screws 10 to the upper ends of said rear legs 8, and bars 9 have the extending bearing studs 11 that extend outwardly from the rear corner of the rear legs and are pivotally secured to the underside of piece 3 by the straps 12 and screws 13. The rear legs 8 are pivoted to the hinged tread piece 3 so that the tops of the rear legs engage the underside of said piece 3 and thus relieve the pivots or studs 11 of strain during use 90 of the stool and the pivots are placed at the rear upper corner of the rear legs so that when the stool is collapsed the sides of the

rear legs can swing toward the underside of the hinged tread piece 3.

The bars 9 are secured to the outside of the rear legs 8 and the rear legs are spaced 5 apart by the round cross bars 14 so that when the bearing studs 11 are in the straps 12 the rear legs 8 are pivoted to but are not detachable from the hinged tread piece 3.

The ends of the rear legs 8 are cut aslant 10 so that when the ladder stool is in erected position they incline rearwardly, outwardly and from under the piece 3. That is, when the appliance is erected for use and the piece 3 is held in a horizontal plane, the rear legs incline rearwardly from the top downward at an angle of about eleven degrees, and sidewise nine degrees.

At each side of the step ladder stool are arranged the pivoted braces 15 which have 20 their upper ends pivotally connected by rivets 16 to the upper ends of the respective legs 5 and angle plates 6, and the other ends of these cross braces are extended downward toward the mid section of the respective rear legs 8 and are pivotally connected thereto by the rivets 17, and these braces prevent forward or rearward movement of the rear legs 8 when the step ladder stool is in erected position, but permit the rear legs to swing 25 toward the step ladder legs when the appliance is lifted.

There are two steps 18 secured between the legs 5. Legs 5 are recessed at 19 to receive the ends of the steps which are secured therein by the nails 20.

Also another means is provided for holding the ends of the steps securely in the recesses 19 which consists of iron rods 21 that are extended under the steps and through the legs 5 and washers 22 that are on the outside of the legs, and the rods are secured in place by riveting. That is, the ends 23 of the rod are expanded by hammering to extend them over and hold the washer securely 45 to the sides of the legs.

Also adjacent the top and between the ends of legs 5 is secured a cross round 24 that aids in making a rigid cross connection between the step ladder legs.

The steps 18 preferably are much wider 50 than the legs 5 with the additional width extended forward beyond the legs, and the top surface of the steps are provided with the noiseless treads 25 that can be formed of rubber or any other flexible material, and these treads can be secured to the steps by 55 any well known means as adhesive paste or by tacking.

Also if desired both the front and rear 60 legs can have noiseless resilient pads 26 on their lower ends so that the step ladder stool can be placed on a highly polished floor, or on a carpet or rug without marring them as previously stated. However, it is understood 65 that the stool can be made either with

or without the pads 26, as there are uses for the step ladder stool in which these pads will not be necessary.

The seat or top tread 1 is provided with the cushion 27 secured to the fixed tread piece 2 and cushion 28 secured to hinged tread piece 3. These cushions comprise resilient packing material 29, 30 over which are arranged the leather sheets 31, 32 that have their edges turned down over the edges 70 of the plates 2, 3 and secured thereto by the tape bands 33 and tacks 34, and the edges of the leather sheets covering the abutting edges of the plates 2, 3 can be secured in 75 place by an adhesive such as glue.

The step ladder stool is erected by simply pivotally moving the rear legs rearwardly from the ladder legs until they are extended to full open position, in which the bottom end surfaces of the ladder legs and the rear legs are in the same plane as the top, and contacting of the bottom ends of the rear legs with a level surface holds the step ladder stool in erected position.

The step ladder stool is collapsed into the 90 position shown in Fig. 3 by placing a hand under the edge *a* and lifting the appliance, and due to the fact that the seat 1 is formed of two hinged sections it will be apparent that in collapsed position the rear section 3 95 will compensate for the difference in length between the front and rear legs thus permitting the ladder to stand erect as shown in Figure 3.

It is thus seen that this newly invented 100 combined ladder and stool comprises the ladder member comprising the legs 5 having a rigidly fixed top member 2; a leg member comprising the rear legs 8 and having a top member 3 hinged thereto and also hinged to the top member 2 of the ladder; and stay brace means formed of the members 15 pivoted at the upper portion to the upper portion 105 of the ladder member and pivoted at its lower portion to a relatively lower portion 110 of the leg member; said stay brace means being aslant and connecting the ladder member and the leg member and preventing further spread of said members from each other when the top members are in practical 115 parallelism with the bevelled bottoms or feet of the ladder member and the leg member.

It is understood that the invention is not limited to the exact specific features minutely described herein and I may make such 120 changes as are within the skill of a mechanic without departing from the main spirit of the invention.

I claim,

A combined stool and stepladder construction, comprising a top tread formed of front and rear sections hinged together, supporting legs rigidly secured at their upper ends to one of the sections of said top tread, treads secured between the supporting legs interme- 125

diate their upper and lower ends, a pair of rear legs pivotally secured at their upper ends to the other section of said top tread for supporting the combined stool and ladder in an operative position, and braces pivotally connecting the supporting legs and rear legs, the construction and arrangement being such that the rear legs and rear tread

section will automatically move to collapsed position when the combined stool and step-ladder is lifted by the front tread section. ¹⁰

In testimony whereof, I have hereunto set my hand at Los Angeles, California, this 4th day of December, 1922.

THOMAS WILLIAM HALL.
